DESIGN FOR A SHOE UPPER MATERIAL

Abraham Turiansky, New York, N. Y.

Application March 27, 1937, Serial No. 68,443

Term of patent 3½ years

To all whom it may concern:

Be it known that I, Abraham Turiansky, a citizen of the United States of America, residing in city of New York, county of New York, and State of New York, have invented a new, original, and ornamental Design for a Shoe Upper Material, of which the following is a specification, reference being had to the accompanying drawing, forming part thereof.

The drawing is a plan view of a piece of shoe upper material showing my new design.

The characteristic feature of my design resides in the combined stitching and cutouts which give the appearance of piping.

I claim:

The ornamental design for a shoe upper material substantially as shown and described.

ABRAHAM TURIANSKY.
